UNITED STATES PATENT OFFICE

BLAIR BURNS CAMPBELL, OF EUREKA, CALIFORNIA

HINGED TOP FOR BOX CARS

Application filed January 8, 1929. Serial No. 331,016.

My invention relates to improvements in hinged tops for box cars, and it consists in the combinations, constructions and arrangements hereinafter described and claimed.

5 An object of my invention is to provide a hinged top for box cars that may be opened for opening the entire top of the car, thus permitting cranes to be used instead of human effort for unloading the cars. This results 10 in a quicker release of equipment, which is a saving to the railroads, and further results in a cheaper handling cost to the shipper, because cranes can do the work of a number of men.

15 A further object of my invention is to provide a device of the type described that has a water-tight roof or top when the top is closed, and which has means for preventing the spreading of the sides of the car when the 20 roof is in closed position. The device has novel means for opening one portion of the roof prior to the other in order to automatically release the locking device, and then for moving one portion of the roof faster than 25 the other for causing both to reach wide-open position at the same time.

Other objects and advantages will appear as the specification proceeds, and the novel features of the device will be particularly 30 pointed out in the appended claims.

My invention is illustrated in the accompanying drawing, in which

Figure 1 is a top plan view of a box car showing my device operatively applied there- 35 to;

Figures 2, 3 and 4 are sections along the lines 2—2, 3—3, and 4—4 of Figure 1;

Figure 5 is an end elevation of the upper 40 part of the box car;

Figure 6 is a section along the line 6—6 of Figure 5; and

Figure 7 is a section along the line 7—7 of Figure 6.

In carrying out my invention, I make use 45 of a standard box car that has vertically-extending braces 1 made of metal, and U-shaped in cross section, and sheathing or siding 2 disposed on the inner sides of the braces 1. In certain types of box cars, the braces are disposed inside of the sheathing. My device is

adaptable to this type of box car, but I have chosen to illustrate the type just referred to.

Figure 4 shows Z bars 3 and 4 extending along the tops of the braces 1. These bars carry bearings 4' and 5 (see Fig. 3). Figure 55 5 shows the bearings as being disposed at the ends of shafts 6 and 7. Additional bearings may be disposed at predetermined points along the shafts in order to properly support the shafts. The shafts extend from end to 60 end of the box car.

I provide a center-opening roof for the box car, and I will refer to the two halves of the roof as being the left half, lettered A, and the right half, lettered B. Each half is carried 65 by roof stringers 8 and 9, and these are secured to angle bars 10 and 11 which in turn are riveted to brackets 12 and 13. The brackets are keyed to the shafts 6 and 7 so as to be 70 swung when the shafts are rotated.

The means for rotating the shafts will now be explained. In Figure 5, I show the shaft 6 as being provided with a segmental gear 14, and the shaft 7 with a segmental gear 15. A cross shaft 16 carries a bevel gear 17 that 75 meshes with the gear 14, while a cross shaft 18 carries a bevel gear 19 that meshes with the gear 15. The gear 17 is larger in diameter than the gear 19.

The reason for this is that I provide angle 80 bars 20 and 21 (see Figure 4) that are carried by the roof portions A and B and that engage with each other when these portions are in closed position for preventing the sides of the car from spreading. It is necessary 85 to have the half B move upwardly before the half A starts to move in order that the two angle bars 20 and 21 may unlock one from the other. The cross shaft 18 is therefore rotated through practically a complete 90 revolution before the cross shaft 16 starts to rotate. This will give the necessary lead to the half B over the half A. It is then necessary to have the half A overtake the half B 95 in order that both will reach wide-open position at the same time. I accomplish this by the two different sized gears 17 and 19, the gear 17 requiring one less revolution to swing the half A into wide-open position than is required by the gear 19.

The means for causing the shaft 18 to take substantially one complete revolution before actuating the shaft 16 is shown in Figures 6 and 7. In Figure 7, I show the shaft 16 as carrying a ratchet 22 having a single tooth 23. The shaft 18 carries a pawl 24. The pawl is normally in full-line position shown in Figure 6. When the hand wheel 25 shown in Figure 5 is rotated for causing the shaft 18 to move counterclockwise in Figure 6, the pawl 24 will take almost a complete revolution until it again comes into contact with the tooth 23. During this movement the shaft 16 remains idle and the half B has been raised a sufficient distance to release the angle iron 21 from the angle iron 20. Further movement of the shaft 18 in the same direction after the pawl 24 contacts with the tooth 23, will rotate the shaft 16 in a counterclockwise direction at the same speed as the shaft 18. As already stated, the two halves A and B will be swung into full-open position and both will reach this position simultaneously.

A spring-pressed trip piece 26 locks the pawl 24 against the tooth 23. This permits the gradual lowering of the two halves A and B and causes the half A to reach its position first. The worm and worm gear connecting the hand wheel with the cross shaft 18 locks the halves A and B against accidental movement. The trip may now be released to permit the other half to swing into closed position.

I provide means for making a water-tight joint along the center of the roof where the two halves join each other. Curved sheet metal sections 27 and 28 overlap each other when the halves are in closed position and form a water-tight joint.

In Figure 1, I show a longitudinal section through a portion of the roof and one of the end walls of the box car. This section is for the purpose of illustrating how the ends of the box car are made water-tight when the roof portions are swung into closed position. The roof stringers 8 and 9 already referred to are U-shaped in cross section as shown in Figure 2. At the edges of the halves A and B, I dispose L-shaped roof stringers 29 that bear against the upper edges of the end walls 30 for forming a water-tight joint. In this way the roof of the box car when in closed position forms a water-tight connection with the side and end walls. The overlapping of the angle irons 10 and 11 on the Z bars 3 and 4 provides a water-tight joint along the sides of the box car.

Although I have shown and described one embodiment of my invention, it is to be understood that the same is susceptible of various changes, and I reserve the right to employ such changes as may come within the scope of the invention as claimed.

I claim:

1. A box car having a roof consisting of two

half sections, shafts extending along the sides of the box car for swinging the sections, a locking device for the two half sections, two aligned cross shafts, segmental gears carried by said first-named shafts, a large and a small bevelled gear carried by said cross shafts and meshing with said segmental gears, a hand wheel operatively connected to the cross shafts carrying the smaller bevelled wheel, a pawl and a ratchet connecting the two cross shafts together, said pawl being carried by the cross shaft carrying the small bevel gear and being designed to make substantially a complete revolution before operatively connecting the two cross shafts together, and manually controlled means carried by said ratchet for locking said pawl thereto.

2. A box car having a roof consisting of two half sections, shafts extending along the sides of the box car for swinging the sections, a locking device for the two half sections, two aligned cross shafts, segmental gears carried by said first-named shafts, a large and a small bevelled gear carried by said cross shafts, a hand wheel operatively connected to the cross shafts carrying the smaller bevelled wheel, a pawl and a ratchet connecting the two cross shafts together, said pawl being carried by the cross shaft carrying the small bevel gear and being designed to make substantially a complete revolution before operatively connecting the two cross shafts together, manually controlled means carried by said ratchet for locking said pawl thereto, and weather strips extending along the abutting edges of said roof sections and overlapping for forming a water-tight joint when the roof sections are closed.

3. A box car having a roof consisting of two half sections, shafts extending along the sides of the box car for swinging the sections, a locking device for the two half sections, two aligned cross shafts, segmental gears carried by said first-named shafts, a large and a small bevelled gear carried by said cross shafts, a hand wheel operatively connected to the cross shafts carrying the smaller bevelled wheel, a pawl and a ratchet connecting the two cross shafts together, said pawl being carried by the cross shaft carrying the small bevel gear and being designed to make substantially a complete revolution before operatively connecting the two cross shafts together, manually controlled means carried by said ratchet for locking said pawl thereto, weather strips extending along the abutting edges of said roof sections and overlapping for forming a water-tight joint when the roof sections are closed, and angle irons carried by the sides of said roof sections and cooperating with the upper edges of the box car itself for providing a water-tight joint.

4. A box car having a roof formed in sections, means for first raising one section and then raising the other, said means causing the

second raised section to move faster in order that both sections reach wide-open position simultaneously.

5. A mechanism for raising two roof sections of a box car and comprising parallel shafts operatively connected to the roof sections, a pair of aligned cross shafts, each cross shaft being connected to one of the parallel shafts by gearing, the gearing on one cross shaft turning its associate shaft more rapidly than the gearing connecting the other shaft with its associate shaft, said cross shafts being connected to each other by a pawl and ratchet designed to permit a complete revolution of one shaft before connecting the two together, and manually controlled means for operating the cross shafts.
